UNITED STATES PATENT OFFICE

149,650

DESIGN FOR AN EXHAUST PIPE FITTING

John C. Kelly, Roscoe, Calif.

Application April 14, 1947, Serial No. 138,357

Term of patent 14 years

(Cl. D14—6)

To all whom it may concern:

Be it known that I, John C. Kelly, a citizen of the United States, residing in the city of Roscoe, county of Los Angeles, and State of California, have invented a new, original, and ornamental Design for an Exhaust Pipe Fitting, set forth in the annexed specification.

Fig. 1 is a top perspective view of an exhaust pipe fitting showing my new design; Fig. 2 is a side elevation of the exhaust pipe fitting; Fig. 3 is an end elevation of the exhaust pipe fitting taken from the righthand end in Fig. 2; Fig. 4 is an end elevation of the exhaust pipe fitting taken from the lefthand end in Fig. 2; and Fig.

5 is a bottom plan view of the exhaust pipe fitting.

I claim:

The ornamental design for an exhaust pipe fitting, as shown.

JOHN C. KELLY.
